UNITED STATES PATENT OFFICE.

EDGAR SAMUEL LYONS, OF TORONTO, ONTARIO, CANADA, ASSIGNOR TO THE McCASKEY REGISTER COMPANY, (INCORPORATED IN 1914,) OF ALLIANCE, OHIO, A CORPORATION OF OHIO.

FILING APPLIANCE.

1,299,746.

Specification of Letters Patent.

Patented Apr. 8, 1919.

Application filed March 26, 1918. Serial No. 224,898.

To all whom it may concern:

Be it known that I, EDGAR S. LYONS, a British subject, residing at Toronto, in the county of York and Province of Ontario, 5 in the Dominion of Canada, have invented certain new and useful Improvements in Filing Appliances, of which the following is a specification.

The invention relates to a filing appliance 10 for sales bills and other similar papers, in which a plurality of bill holders are operatively mounted upon a suitable base for swinging separately or collectively into upright or reclined position for giving access 15 to the filing faces of the holders; and the object of the improvement is to mount and operate such a series of holders upon a base or within a case having substantially the same depth from front to rear as the corresponding 20 depth of the holders when in upright position, so that the appliance as a whole can be placed and operated upon a comparatively narrow shelf or the correspondingly narrow portion of a counter, 25 without protruding in front thereof when the appliance is not in use.

This general object of the improvement is attained by providing swinging and sliding means automatically actuated by the operation 30 of one of the holders, for supporting the holders when one or more of the same are swung into reclined position; and such means may comprise a pair of links or arms pivoted at one end to the sides of the swinging end of the foremost holder, and being 35 in sliding engagement at the other end with the sides of the case so that the forward edge of the case will stop the links or arms in substantially horizontal position.

40 A preferred embodiment of the invention thus set forth in general terms, is illustrated in the accompanying drawings, forming part hereof, in which—

Figure 1 is a front or face elevation of the improved filing appliance showing the holders in normal upright position;

Fig. 2, an elevation section of the same on line 2—2, Fig. 1;

Fig. 3, a similar section showing the supporting means and several of the holders 50 swung forward into reclined position;

Fig. 4, a detached perspective view of the

supporting means for one side of the appliance; and

Fig. 5, a fragmentary sectional view of 55 the slide guide and roller.

Similar numerals refer to similar parts throughout the drawings.

The filing appliance preferably comprises a series of holders 1 normally arranged in 60 upright position with their lower ends connected by hinges 2 and having the forward side of the foremost leaf 1' supported by the pivot pin or pintle 3 upon bearing brackets 4 mounted at or near the forward edge of 65 the base 5 of the rear wall 6 and side walls 7 forming the case of the appliance.

Abutment rollers 8 are preferably mounted upon brackets 9 secured to the side walls of the case against which rollers the rear-most holder is adapted to bear and operate 70 in a well known manner, as the foremost leaves are swung to and from reclined position; and the base 5 of the appliance is preferably provided with means, as the clips 10 75 and the bolts 11 located near the rear of the base, for securing the same to the shelf or counter 12 at or near the forward edge thereof, so that the appliance as a whole will not be tilted forward when the leaves are swung 80 and supported in reclined position as illustrated and described herein.

Supporting arms 13 are provided, preferably one at each side of the holders, which supporting arms are pivoted at one end to 85 the free end of the foremost holder 1', and are provided at the other end with a sliding engagement with the sides of the case along or adjacent to the base thereof.

The pivotal connection for the swinging 90 ends of the supporting arms, may comprise the pivot bar 14 extending from one arm to the other and being journaled in the free end of the foremost leaf; and the sliding engagement for the other ends of the supporting arms, may be by means of the rollers or runners 15, pivoted to the ends of the arms operating in the flattened C-shaped channels 16 secured to the side walls of the case as by means of the L-brackets 17 located 95 in the angles formed by the side walls 7 and the base 5 of the case, which channels form guideways in which the slide rolls are adapted to slide forward and rearward.

The parts are so proportioned and arranged that when the foremost holder is in normal upright position, the slide rollers or runners 15 will be located in the guideways 16 at or near the rear wall of the case, and that when the foremost holder is swung forward into reclined position, the pivoted ends of the supporting arms, are automatically carried forward and downward therewith, 10 until the lower sides or edges thereof intermediate their ends impinge the forward edge 18 of the base in which operation the rollers or runners slide forward in the guideways to a point within the forward ends thereof; 15 and it is evident that the bearing furnished by the forward edge of the base serves to stop the arms 13 in substantially horizontal position for supporting the foremost leaf in reclined position, as shown in Fig. 3, which 20 foremost holder thus becomes a table for supporting the other holders of the series which may be swung forward and superposed in reclined position upon it; and it is also evident that when the foremost holder 25 is swung upward into upright position, the supporting arms will be automatically carried into upright position alongside the holders, and that the rollers or runners on their rear ends will slide rearward in the 30 guideways.

I claim:

1. A filing appliance including a base having guideways and pivotal bearings, a series of swinging holders having the foremost 35 holder pivoted on the bearings, and arms at the sides of the holders having their foremost ends pivoted to the free end of the foremost holder and the rear ends in sliding

engagement with the guideways, and arranged to rest on the forward edge of the 40 base for supporting the holders in reclined position.

2. A filing appliance including a base, a series of normally upright holders mounted on the base for swinging to and from 45 reclined position, and arms having pivotal connection at one end with the foremost holder and guiding engagement at the other end with the base adapted to bear intermediate their ends upon the base for supporting the holders in reclined position.

3. A filing appliance including a base, a series of normally upright holders mounted on the base for swinging to and from 55 reclined position, and means operatively connecting one of the holders and the base adapted to bear upon the base intermediate its connections for supporting the holders in reclined position, said means having pivotal connection with the one and sliding engagement with the other of the connected parts.

4. A filing appliance including a base, a series of normally upright holders mounted on the base for swinging to and from 65 reclined position, and means operatively connecting one of the holders and the base adapted to bear upon the base intermediate its connections for supporting the holders in reclined 70 position, said means having pivotal connection with the one and guiding engagement with the other of the connected parts.

EDGAR SAMUEL LYONS.
